UNITED STATES PATENT OFFICE.

RICHARD HALDENWANG, JR., OF BROOKLYN, NEW YORK.

FAN.

1,141,957.

Specification of Letters Patent.

Patented June 8, 1915.

Application filed July 8, 1914. Serial No. 849,668.

To all whom it may concern:

Be it known that I, RICHARD HALDENWANG, Jr., a citizen of the United States, and a resident of Brooklyn, in the county of 5 Kings and State of New York, have invented certain new and useful Improvements in Fans, of which the following is a specification.

This invention relates to improvements in 10 hand fans and particularly to that class adapted to be folded into small compass.

The objects of the invention are, first, to provide a fan which may be folded, one part past another, for convenience in carrying.

15 A second object is to provide means whereby the fan is automatically held in either a folded position or extended for use. Third, to combine with the fan a carrying means for toilet accessories and the like, 20 and, finally, to provide a fan which can be used as a sun or wind shield, and particularly as an advertising medium.

These and other objects, which will become manifest, are attained by the novel 25 construction and combination of parts hereinafter fully described and shown in the accompanying drawing, forming part of this specification, and in which:

Figure 1 is a side view of the fan folded 30 into its least compass. Fig. 2 is a similar view of the same, as extended for use. Fig. 3 is a cross sectional view of the handle, taken on line 3—3 of Fig. 2. Fig. 4 is a side view showing a modified form of construction in a folded position. Fig. 5 is a similar view of the same extended. Fig. 6 is a fragmentary perspective view taken on line 35 6—6 of Fig. 4. Fig. 7 is a perspective view 40 showing in detail the automatic catch used in holding the fan extended. Fig. 8 is a similar view of the combined stop and guard for holding the blade members when folded. Fig. 9 is a fragmentary perspective view 45 showing in detail a modified form of construction from that indicated in Fig. 6, and, Fig. 10 is a view of the constraining band.

In the simplest form, as shown in Figs. 1 and 2, the entire structure consists of two main elements each comprising a blade section 50 15 and handle 16, both being formed identically alike from any suitable material, as heavy card board, and joined together in pairs, side by side, arranged so that the edge of the right hand element faces the corresponding edge of the left hand element, by

means of a tubular rivet 18, the flanged ends of which hold the elements in close relation but allow them to pivot on the tubular portion of the rivet. The handle sections are formed with semicircular ends 19, from 55 which extend an outwardly curved profile 20 suited to the hand. On the extreme of the handles is applied a reinforcing element 21, the same being held in position by the tubular rivets and having an extension reaching toward the angular corner of the fan, it being caused to adhere to the fan material by any approved method. A tape, ribbon or cord 22 may be passed through the rivet and used as a carrying means as usual. On the 60 opposite edge of the handle, the material is formed substantially parallel as at 23, to the concave portion 24, from whence it is curved outwardly as at 25, the extreme point 26 being symmetrical with the point 27 on the 65 opposite side. Immediately above these points are indentations or recesses 28 and 29 adapted to receive a spring constraining element 30, which may preferably be a rubber band, although obviously any elastic means 70 may be used with like effect.

From the recess 28 the material is beveled outwardly, forming an edge 31, terminating at the corner 32, the upper edge 33 being curved to a radius of which the rivet 18 75 is approximately the center. The opposite corner is bounded by a curve from whence extends the outer edge 34 terminating at the recess 29. Thus it will be seen that when folded, one element is superimposed upon 80 the other and is held in such position by means of the elastic band 30; when the two handle portions are grasped the band is caused to stretch allowing the blade elements to separate, assuming the shape indicated in Fig. 2, forming the conventional 85 shape of a common hand fan. The function of the band is to cause the blade members to assume a folded position as soon as the hand grasp is relaxed and also to hold the 90 members in intimate side contact at all times.

When in the position shown in the dotted lines in Fig. 2 the fan is held in an open or extended position. Thus it is possible to 95 utilize either or both of the adjacent blade surface as a sustaining and transporting means for thin flat articles such as are in frequent demand, for instance, a mirror, comb and face powder receptacle.

In the modified forms shown in Figs. 4 to 9 inclusive the same general construction is maintained with certain additional features pertinent to a higher grade structure. These features consist of a thin metallic reinforcing plate 35, applied to the exterior of the fan handle elements, the same being extended and folded over the edges forming a frame 36 and 37 for the outer and upper edges respectively.

In order that the blade elements may be held in close relation when closed or folded, a metallic clip 38, is secured to one of the blade elements by the rivet 39 in such manner that the reentrantly turned portion 40 forms an open loop receptive of the edge of the other fan blade element. On the opposite corner of the same blade is another rivet 41 pivotally securing an arm 42, having at its end a clip comprised of side walls 43 and 44, joined by the backing 45; also at the end and extending downward between the side walls is a detent 46, adapted to engage with a recess 47 formed in the upper edge of the opposite fan element. This clip makes contact with the rounded corner of the other fan blade when they are folded, substantially opposite the clip 40, but upon exerting pressure to open the fan, the clip 40 is caused to rise as the fan blade elements move in separating until it enters the recess 47, preventing the blades from closing, until it has been withdrawn by releasing the spring 48, the center of which is coiled around the body of the rivet 41 and is provided with a looped end 49 engaging with the upper edge of the fan blade while the other end 50, rests operatively upon the backing 45.

40 The fan blades are arranged with transparent inserts 52, as colored or clear celluloid, either in one or both members, the same being held in place by the fan material 15 as indicated in Fig. 6, or the entire blade 45 may be made of transparent material engaged within a border as shown in Fig. 9.

Thus there is provided an efficient means for protecting the eyes against the glare of the sun, or wind driven particles, with equal facility and without interfering with the use of the device as a fan.

Having thus described my invention, what I claim as new and desire to secure by Letters Patent, is:

55 1. A fan comprised of two like side elements forming integral blade and handle portions, one of said elements being reversed and superimposed upon the other, and a uniting means connecting the handle portions in such manner that they may freely pivot thereon.

60 2. A fan comprised of two side members of uniform contour, one overlying the other and forming respectively blade and handle elements, a tubular rivet pivotally engaging

the handle portions and a constraining means adapted to maintain the member in a normally closed position.

3. A fan comprised of two side members of uniform contour, one overlying the other 70 and forming respectively blade and handle elements, a tubular rivet pivotally engaging the handle portions and a constraining means surrounding the exterior sides and edges of said members whereby they are held 75 normally in a closed position.

4. A fan comprised of two similar sides forming blade and handle portions, a pivotal engaging means securing said sides in such manner that one side may move relative to the other, an elastic band embracing both of said sides thereby constraining them against opening or lateral displacement and means combined with said sides for supporting said band, said side elements being 85 adapted to act as depositories for miscellaneous flat articles.

5. A fan comprised of two similar side members, each constituting a full handle and a partial blade element, one being superimposed on the other, a pivotal connection therebetween, a reinforcement on the exterior of each of said handles, a border formed with said reinforcement extending along the side and upper edges of the blade 95 portion and a constraining means embracingly engaging said blade portions.

6. A fan comprised of two similar side members, each constituting a full handle and a partial blade element, one being superimposed on the other, a pivotal connection therebetween, a reinforcement on the exterior of each of said handles, a border formed with said reinforcement extending along the side and upper edges of the blade 100 portion, a constraining means embracingly engaging said blade portions, and a limiting clip attached to one of said blades adapted to engage with the other when the device is 105 in a closed position.

7. A fan comprised of two similar side members, each constituting a full handle and a partial blade element, one being superimposed on the other, a pivotal connection therebetween, a reinforcement on the exterior of each of said handles, a border formed with said reinforcement extending along the side and upper edges of the blade portion, a constraining means embracingly engaging said blade portions, and a limiting clip attached to one of said blades adapted to engage with the other when the device is 110 in a closed position and a spring clip also engageable therewith, said spring clip being secured to the same blade as is the fixed clip. 115

8. A fan comprised of two similar side members, each constituting a full handle and a partial blade element, one being superimposed on the other, a pivotal connection therebetween, a reinforcement on the ex- 120 130

terior of each of said handles, a border formed with said reinforcement extending along the side and upper edges of the blade portion, a constraining means embracingly engaging said blade portions, a limiting clip attached to one of said blades adapted to engage with the other when the device is in a closed position, a spring clip also engageable therewith, said spring clip being secured to the said blade as the fixed clip, and means combined with said spring clip whereby said device may be retained in an open position.

9. A fan comprised of two side members of uniform contour, one overlying the other and forming respectively blade and handle elements, a transparent insert in one or both blades, a tubular rivet pivotally engaging the handle portions and a constraining

means adapted to maintain the member in 20 a normally closed position.

10. A fan comprised of two side members of uniform contour, one overlying the other and forming respectively blade and handle elements, a tubular rivet pivotally engaging 25 the handle portions, a constraining means adapted to maintain the member in a normally closed position, and a colored translucent panel secured in one or both blade members.

In testimony whereof I have signed my name to this specification in the presence of two subscribing witnesses.
